UNITED STATES PATENT OFFICE.

WILLIAM BALL, OF NEW VIENNA, OHIO.

IMPROVEMENT IN METERS.

Specification forming part of Letters Patent No. 117,366, dated July 25, 1871.

To all whom it may concern:

Be it known that I, WILLIAM BALL, of New Vienna, in the county of Clinton and State of Ohio, have invented a new and valuable Improvement in Water-Meters; and I do hereby declare that the following is a full, clear, and exact description of the construction and operation of the same, reference being had to the annexed drawing making a part of this specification, and to the letters and figures of reference marked thereon.

Figure 1 of the drawing is a plan view of my invention with the lid removed. Fig. 2 is a vertical section of my invention. Fig. 3 is a side elevation of ring with floats swiveled thereto. Fig. 4 is a vertical section of meter-ease with floats removed. Fig. 5 is a plan view of the same.

This invention has relation to certain novel improvements in liquid-meters for measuring and denoting quantities of fluid passing through them. The device to which said improvements apply consists of a funnel-shaped vessel having a cylindrical rim at the upper part thereof, within which is a series of hinged buckets or floats, arranged in radial order around a central vertical rod, which operates an index or other device for denoting quantities. This rod turns with the buckets or floats, which are made to rotate by the action of the water or other liquid, which is admitted to them through a lid covering the cylindrical vessel aforesaid.

Referring to the accompanying drawing illustrating this invention, A represents the funnel-shaped vessel, and B the cylindrical rim. C is the cover, having a tube, D, near its edge, which is inclined slightly, as clearly shown in Fig. 2, so as to cause the liquid to strike the floats in the direction of their rotation around the vertical rod E. F G represent concentric rings encircling the rod E. The outer ring must be of equal height with the rim B, between which and the former the buckets rotate. These rings are secured to the rod E by means of radial arms G', or horizontal plates, or other equivalent means. H designates the buckets or floats, which consist of metallic or wooden plates, of a square or rectangular form, attached to rods h, which extend in radial order through the rings F and G, and are bent at their inner ends, so that when the floats hang in a vertical position said ends may be in contact with pins h', which will effectually pre-

vent the floats from being carried past said vertical positions in the direction of their rotation. I represents a horizontal flange around the inside of the rim B, for a distance of about one-half the circumference thereof. I' represents an inclined flange, which occupies about one-third the circumference of said rim, and meets the flange I at a vertical dividing-plate, K. Between the other ends of these flanges an opening, L, is left for the passage of liquid. M shows a series of horizontal rods extending from the lower part of the rim B to a central point, where they form a bearing for the rod E. They, also, assist in supporting the flanges I I'. The latter are of equal width with the floats H, which in rotating pass over them. The space between any two floats constitutes the bucket, the capacity of which is the standard of measurement for the liquid passing through the meter. The bottom of the bucket is the horizontal flange I. When this meter is in operation, the liquid passing through the tube D strikes the float hanging vertically over the horizontal flange a short distance beyond the dividing-plate K, causing the entire series of floats to rotate. The floats, which are then over the inclined flange I', are by it gradually and in order raised on their pivots toward a horizontal position. The water strikes the float, as above stated, while the one following rests on the dividing-plate K, and as soon as the former begins to move the other drops to a vertical position and closes up the filled bucket, which passes around and is followed by another, filled in like manner, each in order discharging their contents through the opening L, and so the operation continues. At the point where the water first strikes the float a packing, M', commences, and thence continues around the inside of the rim B to the opening L. This is designed to render the seams water and air-tight, and in this connection it may be observed that the meter should work air-tight in every material respect.

The device herein described is particularly applicable to the purposes of a water-meter. Its nature and operation, however, illustrate a principle upon which may be constructed a water-wheel for motive power which will act in an effective manner and entail but comparatively little expense in making it and putting it in operation.

Having fully described my invention, I claim—

1. The combination and arrangement of the

flanges I' I, plate K, ring F, rim B, floats H, tube D, opening L, and funnel A, as and for the purpose specified.

2. In a water-meter, the combination of the rectangular hinged floats or valves H with the annular channel-way, provided with the inclined plane I', and the swelling or packing M' on the inner side of the outer wall B, substantially as specified.

In testimony that I claim the above I have hereunto subscribed my name in the presence of two witnesses.

WILLIAM BALL.
